UNITED STATES PATENT OFFICE

GEORGE T. SCHRÖDER, OF WORCESTER, MASSACHUSETTS

BRIDGE FOR VIOLINS

Application filed March 19, 1928. Serial No. 262,832.

The invention relates to bridges for musical instruments of the viol family, and the object of the invention is to simplify and improve such devices, particularly in respect 5 to fitting the feet to the table of the instrument. As is well known, the tables or bellies of violins vary widely in curvature or arching from the bouts or sides to the crest of the table, the Stradivarius violin, for instance, 10 being of relatively flat form, while those of Steiner are decidedly arched, with various intermediate degrees of arching by different makers depending upon the theory or caprice of the maker. It is frequently necessary or 15 desirable to change or replace the bridge of violins and the like, because of breakage or for various other reasons, and as bridges are supplied to the trade in standard sizes and shapes of feet, it is always necessary to fit the 20 bridge to the particular instrument for which it is intended. This process of correctly fitting the bridge and particularly the feet is a very difficult one and in fact is practically 25 impossible except to the expert repairer or violin maker. This difficulty causes serious 30 inconvenience and annoyance to the player who finds it necessary for immediate replacement of a bridge. To avoid the difficulty referred to, applicant, after much study and 35 experiment, has discovered a simple, inexpensive and highly efficient means for fitting a bridge by providing articulated feet so that the same are self-adjustable to the various contours of the violin tables.

40 The following specification together with the drawings set forth one embodiment of the invention, it being understood the invention is not limited to the precise structural details but that modifications may be made within the scope of the claims. In said drawings, Fig. 1 is a perspective view of a portion of a violin with the improved bridge applied; Fig. 2 is an elevation of the improved bridge showing its application to the top of a violin; Fig. 3 is a fragmentary view of the bridge with the improved foot shown partly in section; Fig. 4 is a section on the line 4—4 of Fig. 3; Fig. 5 is an end view of the bridge with the improved foot.

45

50

In the several figures, 1 designates the body

of the bridge and 2 the articulated feet. The feet 2 comprise slightly arched soles 3 and bifurcated extensions 4. The body of the bridge at either side where the usual feet are provided is adapted to fit snugly within the 55 bifurcated extensions and the parts are secured by rivets 5 passing through the bifurcations and the body of the bridge. Any suitable rivets may be used, but applicant has found it expedient to apply rivets headed at 60 one end and secure the other end by an applied head of any suitable form, the purpose being to avoid tamping and provide a durable connection of the parts. It is noted that the bifurcated extensions 4 of the feet extend 65 well above the pivotal point, thus providing a substantial bearing surface against the body of the bridge on both sides. It is manifest that this feature materially strengthens 70 the construction and avoids the splitting of 75 the bridge, especially at the pivotal points, under normal tension of the strings in a direction longitudinally of the instrument.

In the embodiment of the invention shown, the bottom of the body portion of the bridge, 75 where the usual feet are located, is provided with a rounded extension 6 and the foot is provided at the base of the bifurcations with a flat portion 7, the parts being so constructed that the curved portion 6 contacts with the 80 flat portion 7 when the foot is oscillated.

85 Various materials may be used for the feet, but such material preferably should be of stronger and tougher character than that of the body of the bridge which is usually of maplewood. It has been found that ebony or other hard woods will suffice for the feet but extensive experiments have demonstrated that metal is more efficient for strength and durability and for tonal effect. Aluminum, 90 copper and other metals have been tried but applicant has discovered that brass produces the best tonal results although he is unable to explain the acoustical principles underlying the discovery. Possibly the same principles apply as in the adaptability of brass for bells and carillons.

95 It is obvious that applicant's improvement may be applied to bridges when manufactured, or may be applied to bridges of the 100

common form now on the market by removing the present feet and forming the parts as above described.

I claim:—

- 5 1. A bridge for violins provided with an adjustable foot, said foot having opposed spaced extensions with flat inner surfaces adapted to engage opposite sides of the bridge, and a pivot pin connecting said extensions to the bridge.
- 10 2. A bridge for violins comprising a body portion provided with a curved projection at its bottom edge and an adjustable foot having a seat for said curved projection and provided with opposed spaced extensions with flat inner surfaces adapted to engage opposite sides of the bridge, and a pivot pin connecting said extensions to the bridge.
- 15 3. A foot for violin bridges comprising a base portion and opposed spaced extensions thereon having flat inner surfaces adapted to engage opposite sides of the bridge, and means for pivoting said extensions to the bridge.
- 20 4. A metal foot for violin bridges comprising a base portion and opposed spaced extensions thereon having flat inner surfaces adapted to engage opposite sides of the bridge, and means for pivoting said extensions to the bridge.
